Inventor
William W. Hamilton,
By his Attorneys,
Louis Pagger & Co.

UNITED STATES PATENT OFFICE.

WILLIAM W. HAMILTON, OF MOUNT STERLING, KENTUCKY.

METALLIC FENCE.

SPECIFICATION forming part of Letters Patent No. 363,227, dated May 17, 1887.

Application filed February 5, 1887. Serial No. 226,650. (No model.)

To all whom it may concern:

Be it known that I, WILLIAM W. HAMILTON, of Mount Sterling, in the county of Montgomery and State of Kentucky, have invented certain new and useful Improvements in Metallic Fences; and I do hereby declare that the following is a full, clear, and exact description of the invention, which will enable others skilled in the art to which it appertains to make and use the same, reference being had to the accompanying drawings, which form a part of this specification, and in which—

Figure 1 is a side elevation representing a portion of an iron fence embodying my improvement. Fig. 2 is a vertical sectional view of the same through the line xx in Fig. 1. Fig. 3 is a perspective view of the device for fastening the panels to the line-posts; and Fig. 4 is a similar view of the same device, but showing it in an inverted position.

Like letters of reference denote corresponding parts in all the figures.

My invention has relation to the construction of metallic fences of that class in which the fence consists of a series of panels placed between uprights, or "line-posts," as they are called; and my improvement consists in the combination, with these posts and panels, of a peculiarly-constructed connecting-piece made of iron or other suitable metal, by the use of which the several panels will always be kept in line with one another and in proper position relative to the intermediate line-posts, substantially as will be hereinafter more fully set forth.

On the accompanying drawings, the letters A A denote two adjacent panels connected and supported by the intermediate metallic line-post, B, which may be of any desired construction and braced in any suitable manner.

The letters C, D, and E denote the parallel horizontal rails of the panels, and A and F the pickets, which are inserted through and fastened to the rails in any approved manner.

The connecting and fastening device consists of a metallic plate, G, of rectangular shape, having a downwardly-projecting flange, H, on each side, and being provided with a central square or rectangular aperture, I, between said flanges. On opposite sides of this central aperture are countersunk screw-holes or bolt-

holes J J, and depending from plate G, between the flanges and on opposite sides of the central aperture, I, are downwardly-projecting wings or plates K K, provided with registering-apertures L L, adapted to receive a bolt of suitable thickness. These depending plates or wings K K are somewhat narrower than the body of the top plate, G, so as to form shoulders or offsets M M on each side, as shown in the drawings. This device is placed upon the line-post B by slipping it over the body of the post before the ornamental cap or top piece is placed in position, and then fastening it in its proper place upon the post by drilling a hole 65 transversely through the same and inserting a bolt, N, through said hole and through the apertures L L in the wings K. The appropriate rail, the end of which must be of such a width as to fit between the flanges H H, is then inserted in its proper place and fastened permanently to plate G by means of a screw or bolt passed through the appropriate aperture I. The corresponding rail of the panel on the other side of the line-post is fastened in a similar manner to the projecting part of the plate on that side of the post, so that it will be seen that all the rails of adjacent panels will form one continuous and unbroken line, thus presenting a neat appearance. The wings K K, 70 clamping the line-post and bearing against opposite sides of the same, by reason of their projecting below the flanges at the sides and being separated and free from each other along their edges, will operate not only to hold the 75 device firmly upon the post by means of the bolt N, but by being drawn against the sides of the post will prevent the device from tilting or becoming displaced upon the post, so that the top plate, G, will always be held in a 80 position at right angles to the post, thereby preventing sagging of the connecting-rails.

It follows that a metallic fence constructed with my improved device for attaching the rails and panels will always be properly 95 aligned, and at the same time the panels may readily be removed and again replaced whenever it is desired to do so for repairs or for other purposes.

Having thus described my invention, I claim and desire to secure by Letters Patent of the United States—

1. In a metallic fence, the combination of the line-posts, the horizontal rails, and the fastening and connecting device herein described, the same consisting of a metallic plate provided with parallel side flanges, a central aperture adapted to fit the body of the line-post, and downwardly-projecting wings or plates on opposite sides of said aperture between the flanges, the edges of said wings being separated and not adapted to touch each other, substantially as and for the purpose set forth.
2. As an article of manufacture, the herein-described device for fastening the rails of a metallic fence to and between the line-posts,

the same consisting of a metallic plate provided with parallel side flanges, a central aperture adapted to fit the body of the line-post, and downwardly-projecting wings or plates on opposite sides of said aperture between the flanges, substantially as and for the purpose set forth.

In testimony that I claim the foregoing as my own I have hereunto affixed my signature in presence of two witnesses.

WILLIAM W. HAMILTON.
